UNITED STATES PATENT OFFICE.

JOSEPH DAVISON, OF NEW YORK, N. Y.

PULVERIZER.

SPECIFICATION forming part of Letters Patent No. 657,761, dated September 11, 1900.

Application filed October 24, 1899. Serial No. 734,610. (No model.)

To all whom it may concern:

Be it known that I, JOSEPH DAVISON, a citizen of the United States, and a resident of the city of New York, borough of Brooklyn, 5 and State of New York, have invented a new and useful Improvement in Pulverizers, of which the following is a specification.

My invention relates to an improvement in pulverizers, with the object in view of providing a machine which is more particularly adapted to grinding and pulverizing stone and ore, which machine shall consist of a large grinding-roll and a plurality of small grinding-rolls having a direct frictional contact 10 therewith, the said small grinding-rolls having their body portions reduced to diameters of different sizes for producing passes between them and the large grinding-roll of different depths.

20 A further object is to provide a new and improved means for permitting the smaller rolls to yield slightly away from the main roll when any matter should become jammed between the smaller roll and the larger roll which it 25 would be impossible to crush, thus saving the machine from being wrecked.

A practical embodiment of my invention is represented in the accompanying drawings, in which—

30 Figure 1 represents a front view of the machine with its front plate removed for disclosing the several rolls. Fig. 2 is a side view of the machine, and Fig. 3 is a vertical central section from front to rear through the same 35 in the plane of the line 3 3 of Fig. 1.

The framework of the machine is composed as follows: A side base-plate A is located at each side of the machine, which base-plates are adapted to rest upon a suitable flooring 40 or support. Upon each of these side base-plates A, I provide a pair of upper side plates B and C, the said upper side plates being so secured to the base-plate as to permit one of the side plates to have a slight sliding movement toward and away from the other side plate upon the base-plate. In the present instance I have shown the side plate C as being permitted to yield and the side plate B as being rigidly secured to the base-plate. The 45 side plate C is permitted this sliding movement by passing a bolt c upwardly through

an opening in the top flange a of the base-plate A and through an elongated slot c' in an outwardly-extended flange c² at the bottom of the plate C. The plate B is held rigidly 55 in position by means of a bolt b, which extends upwardly through a hole in the flange a and through a hole in the outwardly-extended flange b² at the base of the plate B, the two flanges being securely fastened together by setting up the nut b'.

The pairs of side plates B and C are held snugly together, except under undue strain, in the following manner: At the bases of the side plates B and C, I provide a bolt D, which 65 extends longitudinally through a pair of outwardly-extended lugs b³ b⁴ of the plate B and a similar pair of lugs c³ c⁴ of the plate C, the end of the bolt b being screw-threaded and extended a considerable distance beyond the 70 front of the machine. An adjusting-nut d is engaged with said screw-threaded end of the bolt D, and a heavy coil-spring d' is interposed between the said nut and the lug c⁴ of the plate C, the tension of the said spring d' being exerted in a direction to hold the bases of the side plates together. The tension of the spring d' may be adjusted by means of the nut d.

To hold the upper ends of the plates B and C together, I provide a bolt E, which extends longitudinally through a double lug b⁵ at the top of the plate B and a double lug c⁵ at the top of the plate C. The free end of the bolt E is screw-threaded and projects a considerable distance to the front of the machine, and the screw-threaded end is provided with an adjusting-nut e. A heavy coiled spring e' is interposed between the adjusting-nut e and the double lug c⁵, the tension of the said 85 spring being exerted in a direction tending to hold the tops of the plates B and C together. The tension of the spring e' may be adjusted by means of the nut e.

The side base-plates A may be rigidly 95 spaced apart by a plurality of tie-rods a', each of which tie-rods has an adjustable lock-nut connection a² with each of the side base-plates A. The pairs of side plates B and C are rigidly spaced apart by a plurality of tie-rods b⁶ and c⁶, each of the tie-rods b⁶ having an adjustable lock-nut connection b⁷ with each of

the side plates B and each of the tie-rods c^6 having a similar adjustable lock-nut connection c^7 with each of the side plates C.

A central drive-shaft F is mounted in pairs 5 of side frames B and C. This shaft F has keyed thereto the large main grinding-roll G in the space between the two pairs of side plates. The shaft is provided upon one side of the machine (in the present instance the 10 left-hand side) with a suitable drive-pulley f, which may be driven in any suitable manner—such, for instance, as by a belt f', leading from a source of power, not shown herein.

A plurality of small roll-shafts (in the present instance four of these shafts are shown) 15 are mounted in the side plate C at equal distances from the main roll-shaft F, spaced from the grinding-roll G, which small roll-shafts are designated by H I J K. These 20 shafts are provided with small grinding-rolls h i j k, respectively, which rollers are of the same diameter at their ends and are in direct frictional engagement with the periphery of the large roller G, so that the said small rollers are driven by the rotary movement of the 25 large roller.

Wide shallow circumferential grooves of different depths are formed in the small grinding-rolls intermediate their ends, the 30 grooves being formed of gradually-lessening depths from the top roll h to the bottom roll k, so as to produce a progressive grinding of the material being treated as it passes from the top of the machine between the successive small grinding-rolls and the large 35 grinding-roll.

A pair of pulverizing-rolls l and m are carried by outside shafts L and M, which shafts are mounted between the side base-plates A 40 of the machine. These pulverizing-rollers are located in position to receive the ground material as it drops from the bottom grinding-roll k and serve to complete the process of pulverizing the material being treated. 45 The shaft L is mounted in stationary bearings, and it is provided upon one side of the machine with a suitable pulley l', which is driven at a high rate of speed by means of a belt l', leading to a larger pulley f'', carried 50 by the main drive-shaft F. The shaft M is mounted in movable bearings, so that the roll m may be moved toward and away from the roll l, the means which I have shown herein comprising a wedge-block N, interposed between the bearing m' in each of the side base-plates A and the base-plate, the said wedge-block N being controlled by an adjusting-screw n.

A hopper O may be carried by the machine 60 between the pairs of side plates in position to

feed the material into the space between the top small roll h and the large grinding-roll G. Guide-partitions P p may be placed in position to guide the material as it falls from the grinding-roll k to the pulverizing-rolls l and m. 65

The front and back of the machine may be protected by plates Q q, extending from the top of the machine between the pairs of side plates to the side base-plate A.

To insure an extended bearing for the main 70 roll-shaft F, outwardly-extended semicylindrical lugs b⁸ and c⁸ may be provided on the side plates B and C, the said lugs having a suitable lining-sleeve f⁸, of some suitable bearing metal. Similarly each of the small 75 grinding-roll shafts may be provided with an extended bearing in the side plates C by providing the side plates with outwardly-extended lugs c⁹, which may be provided with suitable lining-sleeves c¹⁰, of some suitable bearing 80 metal.

In the structure hereinabove set forth I provide for a progressive grinding of the material and a final pulverization of the same in a simple and effective manner, the structure 85 at the same time being very strong and not liable to get out of order. Should a piece of material be fed to the machine which is too hard to be crushed, the side plates C would be forced slightly away from the side plates B, 90 thus preventing the wrecking of the machine.

It is evident that changes might be resorted to in the form and arrangement of the several parts without departing from the spirit and scope of my invention. Hence I do not wish 95 to limit myself strictly to the structure herein set forth; but

What I claim is—

In a pulverizer, the combination with a smooth-faced large grinding-roll, of a plurality of smaller grinding-rolls having their ends of uniform diameters, the said ends being normally in direct frictional engagement with and driven by the large grinding-roll, each of the said small grinding-rolls having a shallow 100 circumferential groove therein intermediate its ends, the grooves in the several small grinding-rolls being of gradually-lessening depths from the top small roll to the bottom small roll for producing successive reductions 105 of the material being treated, substantially as set forth.

In testimony that I claim the foregoing as my invention I have signed my name, in presence of two witnesses, this 19th day of October, 1899.

JOSEPH DAVISON.
